UNITED STATES PATENT OFFICE.

ALBERT G. LARSON, OF PIEDMONT, CALIFORNIA, ASSIGNOR TO LYDIA F. LARSON.

WASHING-MACHINE MECHANISM.

Application filed June 27, 1927. Serial No. 201,737.

This invention relates to clothes washing machines and the like, and especially to improvements in washing machines of the plunger actuated type.

- 5 There are a number of so-called plunger type actuated washing machines, see for instance, the type disclosed in the patent to E. Lindberg, 1,523,027, issued January 13, 1925, in which a rotary and reciprocal movement is transmitted to the plunger. It has been found by practical experience that machines of this character are not altogether satisfactory as the rotary movement taken by the plunger tends to pile the clothing in one end of the
- 10 tub after the washing operation ceases, thereby requiring more or less constant attention and redistribution of the clothing by the operator in order to insure thorough washing of all of the clothing.
- 15 20 The object of the present invention is to generally improve and simplify the construction and operation of machines of the character described; to provide a plunger movement whereby piling up of the clothing is entirely eliminated; and further to provide a pair of plungers which cooperate to increase the efficiency of the washing operation and at the same time reducing the time usually required to wash certain fabrics. The washing ma-
- 25 chine mechanism is shown by way of illustration in the accompanying drawings in which:
- 30 35 Fig. 1 is a side elevation of the washing machine mechanism showing it in position on a wash tub,

Fig. 2 is an end view of the washing machine mechanism, said view being partially in section.

- Referring to the drawings in detail and particularly Fig. 1, A indicates a base plate which is adapted to be supported on the upper edge of a wash tub such as indicated at B. Mounted on the base plate is a driving motor C, and connected therewith is a reduction gear drive generally indicated at D. The reduction gear drive connects with a worm pinion gear 2 which is secured on a motor shaft 3. This pinion meshes with a worm gear 4 secured on a shaft 5. The shaft 40 is journaled in the housing D and projects through one side thereof, and a crank 6 is secured on the outer end of the shaft. Pivotally mounted as at 7 is a rocker arm or beam 8, and connecting said beam with the crank 6 is a connecting rod 9. Adjustably fixed as at 10 in bearings at the outer or free
- ends of the beam 8 are plunger rods 11 and mounted on the lower ends thereof are plunger cups 12 of suitable construction. The bearings for the plunger rods are arranged 60 tangential to an arc described about the central pivotal support of the said rocker arm or beam 8.
- In actual operation the power of the motor is transmitted through the shaft 3 and the 65 reduction gears 2 and 4 to continuously rotate the shaft 5 and the crank-arm 6 in the direction of arrow a. This continuous rotation of the crank-arm is transmitted through the connecting rod 9 to rock the beam 8 and the 70 plunger rods and cups carried thereby so that they alternately assume the dotted line positions indicated at 8^a and 8^b. Each cup is thus alternately raised and lowered with relation to the water and the clothes in the tub, 75 and this movement causes the water to be circulated back and forth through the meshes of the fabric to wash the same. The plungers, during upward movement, swing away from the center of the tub, and conversely, during 80 downward movement swing toward the center of the tub. The plunger indicated at 12^a thus has a tendency to move the clothing in the direction of arrow b into a position where it will be engaged by the plunger 12^b during its downward stroke, and the plunger 12^b in turn tends to move the clothes towards the plunger 12^a in the direction of arrow c during its downward stroke. In other words, 85 each plunger tends to move the clothes under 90 the other plunger or towards the center of the tub and the clothing is thus placed in a position where it is most efficiently acted upon by the plungers. The clothing is at the same time shifted back and forth through 95 the water and further washing action is obtained due to the flow of the water through the fabric. The efficiency of the machine is further increased by the use of the two plungers as two plunger strokes are obtained during each revolution of the crank 6 where only one plunger action is obtained in the usual type of single acting plunger machines. The time required to wash a certain quantity 100 of fabric is thus practically reduced to one-half as two plunger strokes are obtained during each revolution of the crank. The length of the plunger stroke is more or less dependent upon the length of the beam 8, but the beam is provided with one or more sockets 110 such as indicated at 10 and 10^a for the reception of the plunger rods 11 which may

be shifted inwardly or outwardly on the beam. Thus the plunger stroke may be increased or decreased to suit varying conditions.

5 While certain features of the present invention are more or less specifically described, I wish it understood that various changes may be resorted to within the scope of the appended claims. Similarly, various materials and finishes of the several parts employed may be such as the manufacturer may decide or varying conditions or uses may demand.

Having thus described my invention, what 15 I claim and desire to secure by Letters Patent is:—

1. An agitator for washing machines comprising a bar constituting a rocker arm, a central pivotal support for said bar, bearings 20 carried by the free ends of the bar and ar-

ranged tangentially to an arc described about the central pivotal support, and plunger cups having rods adjustably fixed in said bearings.

2. An agitator for washing machine comprising a bar constituting a rocker arm, a central pivotal support for said bar, bearings carried by the free ends of the bar and arranged tangentially to an arc described about the central pivotal support, plunger cups 30 having rods adjustably fixed in said bearings, a crank shaft disposed above the central pivotal support of the bar, a link connected at its upper end to the crank shaft, and a connection between the lower end of the link and the bar, said connection being at a point intermediate of one of the rods and a pivotal support of the arm.

ALBERT G. LARSON.
